United States Patent Office.

BENJAMIN F. CUNNINGHAM AND JEFFERSON F. CUNNINGHAM, OF FLORA,
ILLINOIS.

Letters Patent No. 72,459, dated December 24, 1867.

IMPROVED BURGLAR-ALARM.

The Schedule referred to in these Letters Patent and making part of the same.

TO ALL WHOM IT MAY CONCERN:

Be it known that we, BENJAMIN F. CUNNINGHAM and JEFFERSON F. CUNNINGHAM, of Flora, is the county of Clay, and State of Illinois, have invented a new and improved Burglar-Alarm, for preventing burglars from entering a door without alarming the inmates of the house; and we do hereby declare that the following is a full and exact description thereof, reference being had to the accompanying drawings, and to the letters of reference marked thereon.

To enable others skilled in the art to make and use our invention, we will proceed to describe its construction and operation.

The alarm parts and bell are such or similar to those used for attaching to clocks. We secure the alarm and bell on a block of wood of sufficient size for practical use. We secure a hook, A, in the upper end of the block, to which the alarm is secured. We suspend the alarm by placing the hook on the spindle of the door-lock. We make fast one end of a wire, E, close to the lower end of the block, then extending up until opposite the hook A. A lever-wire, D, is arranged across the top of wire E. On a hinge, or its equivalent, the wire C, leading from the axle to which the verge is made fast, is bent down and brought over on the outside of wire E. Close to the upper end of the block we secure sheet brass or tin for covering the works, for protection, and obviating dust.

Operation.

Bring down the end of lever D and place under a wire catch, which is secured in the edge of the block marked F. While bringing down the lever D brings back the upper end of wire E, which comes against wire C, which moves the lower verge-tooth deep in gear and cannot escape, the spring may be wound up, and then it is ready for applying to the spindle of the lock. When suspended by the hook A, remove the lower end of lever D from the catch F, and place the opposite end of the lever against the centre of the spindle, then, by turning the knob, it turns the spindle also, which causes the end of lever D to slip off and come forward with the upper end of wire E, which releases wire C and gives free escapement to the verge, which causes the hammer to act on the bell and alarms.

What we claim as our invention, and desire to secure by Letters Patent, is—

The arrangement of lever-wire D, in combination with wire E, for the purpose herein specified.

BENJAMIN F. CUNNINGHAM,
JEFFERSON F. CUNNINGHAM.
